COMBINED CHECKOUT COUNTER AND DISPENSING MACHINE

Paul L. Hittinger, Dayton, Ohio, assignor to The National Cash Register Company, Dayton, Ohio, a corporation of Maryland

Filed Jan. 11, 1961, Ser. No. 63,528

Term of patent 14 years

(Cl. D80—2)

FIG. 1

FIG. 4

FIG. 1 is a rear perspective view of a combined checkout counter and dispensing machine, showing my new design;

FIG. 2 is a front perspective view thereof;

FIG. 3 is a fragmentary elevational view of the left side thereof; and

FIG. 4 is a fragmentary elevational view of the right side thereof, the change return tray being omitted for convenience of illustration.

The characteristic features of my design reside in the appearance of the dispensing machine in association with the full-line portions of the checkout counter as shown.

I claim:

The ornamental design for a combined checkout counter and dispensing machine, as shown and described.
